UNITED STATES PATENT OFFICE.

HENRIE CLAUSS, OF FREMONT, OHIO.

DISPLAY-CARTON.

SPECIFICATION forming part of Letters Patent No. 735,467, dated August 4, 1903.

Application filed October 17, 1902. Serial No. 127,730. (No model.)

To all whom it may concern:

Be it known that I, HENRIE CLAUSS, a citizen of the United States, residing at Fremont, in the county of Sandusky and State of Ohio, have invented certain new and useful Improvements in Display-Cartons; and I do hereby declare the following to be a full, clear, and exact description of the invention, such as will enable others skilled in the art to which it appertains to make and use the same.

This invention relates to a display-carton designed particularly for the packing and displaying of cutlery, such as pocket-knives, razors, scissors, and the like; and it consists of certain novel constructions, combination, and arrangement of parts, as will be hereinafter described and specifically claimed, a box constructed preferably of cardboard and having a cover, which latter is provided with a top portion of cloth, preferably of plush, which latter has its edges turned under all around and secured down upon the cover of the box in this position so as to present a smooth finished raised edge all around, the construction and arrangement being such that the box can be used to pack and ship the goods in and when arriving at their destination to serve as a fancy display-case for exhibiting the same.

The object of my invention is the production of a carton which can be used to pack and ship the goods in and afterward be displayed in or upon a show-case to display the goods to the best advantage, the plush cover or top forming a very attractive and artistic background for the goods.

In the accompanying drawings, Figure 1 is a perspective view of a box constructed in accordance with this invention. Fig. 2 is a vertical longitudinal section through the cover and a portion of the body of the box, showing the manner of constructing the cloth-finished portion of the cover and also of hinging the cover to the main body portion. Fig. 3 is an enlarged detail perspective view of a portion of the cover or lid and the cloth-finishing portion, the latter being raised and the parts separated to show better the construction and arrangement. Fig. 4 is a vertical transverse section through the lid and cloth-finishing portion attached thereto and showing the said cloth-finishing portion slightly raised above the lid and the edge of the lid

extending beyond said cloth-finishing portion. Fig. 5 represents a detail sectional view taken on the plane of line 3-3 of Fig. 1.

55

In the accompanying drawings, 1 represents the main body portion of the box, which may be of any desired size and shape and constructed of any suitable material, but preferably cardboard, which latter is preferably not covered with any cloth-finishing material.

The sides and ends of the box are preferably not covered with such material in order to lessen the expense, though I do not wish to confine my invention to any particular construction in reference to the main body portion of the box. The invention being particularly designed to display cutlery—such as pocket-knives, table-knives, razors, scissors, and the like—paper boxes not provided with cloth-finished sides and ends will answer to the purpose. The cover or lid 2 of the box is secured to the body portion thereof in any suitable manner, but preferably by hinging at one end, as at 3. To the outer surface of the lid or cover is secured a cloth-finishing portion, as 4, preferably constructed of plush, which latter preferably extends substantially the entire length and width of the cover with the exception of leaving a narrow border or margin all around, as at 5. This exposed portion of the lid 5 is preferably covered with an ornamental covering, as silver or gold paper, which adds very much to the appearance of the box. The plush or other finishing-cloth 85 is secured to the lid or cover as follows:

A piece of filling or shaping material, which is preferably of cardboard, is cut of a length and width to fill the space on the top of the cover, so as to allow the exposed portion or margin 5 all around, as just described. A piece of plush or other finishing material, as 7, is then cut of a size slightly larger than said cardboard 6, so that it can be stretched over the said cardboard and have its edges turned under the latter and secured thereto, preferably by gluing. By this construction and arrangement no rough or uneven edge is left, but, on the contrary, a smooth finished edge is secured all around.

95

By the use of the interposed cardboard 6 the finishing-cloth or plush covering 7 is not only stiffened and given a substantial body, but it is raised from the surface of the cover,

100

which adds decidedly to the general appearance and attractiveness of the box and also enables the cloth finish or plush to be tightly stretched and secured in such stretched condition on the cardboard. This greatly facilitates putting the plush in position on the cover and necessarily lessens the expense of manufacture, as a workman of ordinary intelligence can rapidly secure the plush finishing 5 in position on the cover, which would be very difficult to accomplish if it were attempted to turn the edges of the cloth under and paste the same directly to the cover of the box without using the stiffening or attaching piece of 10 cardboard.

It will be observed that a number of articles—such as knives, razors, or scissors—can be packed in one of these boxes, and when received by the dealer one of said articles may 15 be removed from the box and exhibited on the finished lid or cover, the cloth finishing, preferably plush, giving a very fine background and adding much to the display of the goods. If desired, a holding-loop, as 8, can be provided on the top of the lid to hold the article 20 displayed in position so that the box can be turned to a tilted or inclined position without liability of said article falling off. It will also be observed that by placing a number of 25 these boxes in the bottom of a show-case side by side it will practically give to the appearance of the show-case the effect of having a plush or cloth finished bottom, so that articles can be displayed on the tops of said boxes 30 in any manner desired and with pleasing effect, and at the same time the boxes will be serving the purpose of holding the regular stock.

As best shown in Fig. 5 of the drawings, I 35 contemplate employing in connection with the present improved cover a tab 9 for facilitating the raising of a lid, said tab being grasped by the operator for lifting the lid upon its hinge. The tab consists, preferably, of a loop 40 of suitable ribbon, tape, or other material passed through the upper edge of the lid and having its ends extending along the inner surface thereof, a suitable fastener 10 being employed for securing said ends against removal. The fastener 10 is preferably of the 45 two-prong type, having a head or button 11 and having the prongs passed through the material of the cover and through the ends of said tab and spread in the common manner for retaining the parts in the manner described. It will of course be understood that the tab 9 need not be a loop, but may be only a single 50 strip of material. In order to retain the inner ends of the loop-forming tab 9 against falling laterally or being displaced, I may apply a 55 suitable adhesive thereto, so as to secure the same to the inner face of the cover of the box.

Having thus fully described my invention, what I claim as new, and desire to secure by 60 Letters Patent, is—

1. As an improved article of manufacture a

carton for packing, shipping and displaying articles, comprising in its construction a suitable body portion, a cover or lid therefor, said cover having mounted on its upper surface a 70 cloth or finishing portion, which latter is of less length and width than the cover and is formed by stretching the cloth over a piece of stiffening material and turning the edges of the cloth under the edges of said material between it and the top of the cover, and securing the same to said stiffening material, and securing the stiffening material and cloth to the top of the cover so as to present a finished edge of less width and length than the cover, 75 the upper surface of the finishing portion being on a plane above the upper surface of the edge of the cover.

2. A display-cover for a box, comprising a body portion, a finishing material raised above 80 and resting upon the upper surface of the cover, the material of said raised portion being folded under at the edge a short distance within the edges of the cover, the said folded edges making a raised portion upon the cover 85 all around near the edge thereof and leaving an edge all around at a lower plane than the surface of the finishing material, substantially as described.

3. As an improved article of manufacture, a 90 packing, shipping and display carton, comprising in its construction a suitable body portion, an ornamental cover or lid therefor, which latter carries upon its upper surface a piece of finishing-cloth, as plush, which is 95 stretched over a piece of stiffening material and has its edges turned under the edges of said stiffening material and secured thereto, the stiffening material being of less length and width than the cover proper and secured to 100 the top of said cover so as to leave an ornamental edge lower than the finishing-cloth all around, substantially as described.

4. As an improved article of manufacture, a 105 packing, shipping and display carton, comprising a suitable body portion, an ornamental cover therefor carrying on its upper surface a covering of finishing-cloth, such as 110 plush, which latter is stretched over and has its ends turned under and secured to the under side of a piece of stiffening material, so as to be between it and the top of the cover at a distance from its edges, the whole secured to the top of the cover so as to leave a narrow 115 ornamental border all around the thickened edges of the finishing-cloth, elevating the said cloth a considerable distance above the lid, substantially as described.

5. A display-cover for boxes comprising a body portion, a finishing layer of less width 120 and length than the body portion, placed upon the top of the cover, said layer comprising a stiffening piece and a finishing-cloth stretched over the same, the edges of the cloth being turned under the edges of the stiffening material and secured between the same and the 125 upper surface of the cover, leaving an edge 130

on the cover all around, which is on a lower plane than the surface of the finishing material, substantially as described.

6. A display-cover for a box, comprising a body portion and finishing material raised upon and resting upon the upper surface of the cover, the material of said raised portion being folded under at the edge at a short distance within the edge of the cover, the said folded edges making a raised portion upon the cover all around near the edges thereof,

thus leaving an edge all around at a lower plane than the surface of the finishing material, said edge being ornamented with a strip of finishing material, substantially as described. 15

In testimony whereof I hereunto affix my signature in presence of two witnesses.

HENRIE CLAUSS.
